PULVERULENT MATERIAL TREATING
APPARATUS

Edward Butts, Georgetown, Colo.

Application February 18, 1936, Serial No. 64,589

1 Claim. (Cl. 259—18)

This invention relates to an ore mill apparatus for the treatment of tailings and has for the primary object the provision of an economical means to receive and treat tailings to form the latter into a mass which, when mixed with gravel, forms an excellent road surfacing material and may be stored for periods of time without danger of disintegrating or breaking up into small particles and blowing or washing away into streams, 5 and consequently eliminates stream pollution by tailings from mills.

With these and other objects in view, this invention consists in certain novel features of construction, combination and arrangement of parts 15 to be hereinafter more fully described and claimed.

For a complete understanding of my invention, reference is to be had to the following description and accompanying drawing, in which—
20 Figure 1 is a vertical sectional view illustrating an apparatus constructed in accordance with my invention.

Figure 2 is a bottom plan view partly in section illustrating a spray nozzle.
25 Referring in detail to the drawing, the numeral 1 indicates a suitable tank mounted on a supporting structure 2 and provided with an inclined bottom 3, the inclination of which is in the direction of a discharge opening 4 provided with a control gate 5. The top of the tank is equipped with a vent pipe 6 controlled by a damper 7. The tank is also provided with a man-hole 8 normally closed by a removable cover 9.

Leading to the upper portion of the tank is a 30 conveyor tube 10 and extends from a mill for the purpose of delivering fine particles of tailings into the tank 1. A power driven fan 11 is located in the tube 10 for forcing by air pressure the tailings into the tank. An endless conveyor 12 leading from the mill (not shown) extends into the tank and is employed for conveying into said tank larger particles of tailings which could not be successfully passed into the tank by the conveyor tube 10. A hood 13 is arranged in the tank over the discharge end of the endless conveyor 40 45 12 for directing the tailings discharged by the tube 10 away from the discharge end of the endless conveyor.

A reservoir 14 is adapted to receive crude oil 50 with a diluting agent such as gasoline or kerosene by way of a filling neck 15. A power driven agitator 16 operates in the reservoir for thoroughly mixing the oil therein. An air supply pipe 17 leads into the reservoir from an air pressure source (not shown). An outlet pipe 18 extends from the reservoir upwardly to a point ad-

jacent the upper end of the tank 1 and is equipped with a jet 19 extending into a mixing chamber 20 located at the upper end of the tank and to which is connected a spray nozzle 21 in the form of a coil having a series of perforations formed in the underside thereof so that the liquid and air discharging will be in a downward direction with respect to the tank 1. The jet 19 is provided with a regulating valve 22 and the inlet pipe 18 has a control valve 23. An air supply pipe 24 leading from the air supply is connected to the mixing chamber 20 and has a control valve 25.

In operation, tailings from a mill are fed into the tank 1 by both of the conveyors or either and at the same time the oil mixture of the reservoir passes into the tank 1 in the form of a mist or vapor causing the tailings to become impregnated therewith and settle to the bottom of the tank in a mass, which after a period of time may 15 be removed by opening the gate 5. Any gases or back pressure accumulating in the tank may 20 be removed by way of the vent 6. The oil mixture from the reservoir is delivered to the mixing chamber 20 in an atomized state by the jet 19 and the 25 mixing chamber receives air under pressure forcing the vaporized oil through the coiled distributing pipe and escapes therefrom in a downward direction. The tailings after being treated in the tank 1 and removed therefrom may be 30 stored for a period of time without danger of breaking up or blowing away or washing away. The tailings in the mass formation when mixed with gravel will provide an excellent road surfacing material.

Having described the invention, I claim:
An apparatus for treating ore tailings comprising a tank, discharge means for said tank, vent means for said tank, pneumatic and endless conveyors connected to said tank for delivering tailings of different grades into said tank with one grade of tailings delivered into the tank above the other grade of tailings, a mixing chamber extending into the upper end of the tank above said conveyors, a jet extending into said mixing 40 45 chamber, a perforated coiled discharge pipe connected to the mixing chamber and arranged in the tank above the discharge ends of the conveyors, an air supply pipe connected to the mixing chamber, a supply pipe connected to the jet, a reservoir connected to the supply pipe of the jet and adapted to receive liquid ingredients capable of forming a binder, and a power driven agitating means operating in said reservoir. 50 55

EDWARD BUTTS.
